CLAIM

The ornamental design for a tire cleaning kit, as shown and described.

DESCRIPTION

FIG. 1 is a perspective view of my design;

FIG. 2 is a front elevational view of my design, the opposite side view being a mirror image thereof;

FIG. 3 is a top view of my design;

FIG. 4 is a left side view of my design;

FIG. 5 is a right side view of my design; and,

FIG. 6 is a bottom view of my design.

The tire shown in broken lines in FIG. 1 are shown for illustrative purpose only and form no part of the claimed design.
